UNITED STATES PATENT OFFICE.

OSCAR ILLI, OF POCATELLO, IDAHO.

DOOR-HANGER.

1,234,032.

Specification of Letters Patent. Patented July 17, 1917.

Application filed January 8, 1916. Serial No. 71,045.

To all whom it may concern:

Be it known that I, OSCAR ILLI, a citizen of the United States, residing at Pocatello, in the county of Bannock and State of Idaho, have invented new and useful Improvements in Door-Hangers, of which the following is a specification.

This invention relates to improvements in car door hangers and operating mechanism therefor.

In carrying out the present invention, it is my purpose to provide a car door which may be moved to open and closed positions without the aid of rollers and guide tracks and analogous devices now generally in use.

To this end the invention consists in the construction, combination and arrangement of parts hereinafter set forth in and falling within the scope of the claims.

In the accompanying drawings:

Figure 1 is a fragmentary side elevation of a car equipped with a door and lever mechanism constructed in accordance with my present invention, the lever mechanism being shown in dotted lines.

Fig. 2 is a diagrammatic view of the lever system.

Fig. 3 is an enlarged fragmentary horizontal sectional view through the sections constituting the door.

Referring now to the drawings in detail, 1 designates one side wall of a car, such side wall being formed with a door opening 2. Suitably secured to the side plate 35 of the car, above the side of the door opening are pivot bolts 3 and 4, spaced to obtain the desired movement of the door. Suitably fastened to the side sill of the car, below the edge of the door opening is a 40 bracket 5 carrying pivot bolts 6 and 7 spaced to obtain the desired movement of the door.

8 designates the car door and, in the present instance, this door comprises an inner 45 metal sector 9 and an outer metal section 10; and interposed between the sections 9 and 10 at the opposite edges of the door are vertical connecting bars 11 equipped with inwardly projecting lugs 12, disposed along 50 the bar and formed with openings alining with openings in the sections of the door to receive securing bolts or rivets 14, whereby the sections 9 and 10 may be held in spaced formation and against relative movement.

Each connecting bar 11 carries a strip 15, 55 having the end portions thereof fastened to the connecting bar and the central portion bulged or angular. Said strips are equipped with lugs 16, formed with openings respectively alining with openings in the sections 9 and 10 of the door. Through these alining openings are passed securing bolts 18 co-operating with the bolts 14 to maintain the sections 9 and 10 in door formation. In this instance, each metal section 9 and 10 of the door is corrugated so as to strengthen the door. The respective corners of the door may be protected by means of shields 19 constructed of metal or any other material and secured to the sections 9 and 10 at the corners, while fastened to the outer section of the door adjacent to the lower edge thereof and spaced horizontally about as shown are reinforcing plates 20 carrying pivot bolts 21 and 22 respectively. 65 These pivot bolts 21 and 22 terminate short of the inner section 9 of the door in order to accommodate the levers 23 and 24 herein-after described. Arranged between the sections 9 and 10 of the door are levers 23 and 70 24 and the lower end of the lever 23 is mounted upon the bolt 21, while pivoted to the upper end of such lever 23 at 6' is the inner end of a link 25, and the other end of the link 25 is pivoted upon the bolt 3. The 75 lower end of the lever 24 is mounted upon the bolt 22, while the upper end thereof is pivoted at 7' to the inner end of a link 25' and the remaining end of the link 25' is 80 pivoted upon the bolt 4. Pivoted to the lever 23, at a point 23' thereof suitably located to determine the desired movement of the door, is one end of a supporting bar or lever 26, while the remaining end of the lever 26 is pivoted upon the bolt 6 carried by 85 the bracket 5. Another supporting bar or lever 27 has one end pivoted to the lever 24, at a point 24' of such lever 24 to suitably determine the desired movement of the door, and the remaining end mounted upon the 90 bolt 7 carried by the bracket 5.

In practice, when the door is moved longitudinally of the adjacent side wall of the car to cover or uncover the door opening, the lower ends of the levers 23 and 24 swing on 105 and travel with the moving pivot bolts 21 and 22 respectively, while the lower ends of the bars 26 and 27 fulcrum upon the sta-

tionary pivot bolts 6 and 7 swing about such bolts and the upper ends describe the arcs shown by the dotted lines in Fig. 2 of the drawings. In the upward movement of the levers 23 and 24 under the action of the bars 26 and 27, the links 25 and 25' swing upwardly in conjunction with the desired movement of the door. Thus we may call 6' and 7' swinging pivots, and 23' and 24' intermediate pivots. Referring now to the diagram shown in Fig. 2, when the door moves to open position, the right hand angular strip 15 travels away from the angle 7', 24', 7, and the latter changes from a re-entrant angle to a salient angle as seen in dotted lines at the extreme right of this view. Meanwhile, the salient angle 6', 23', 6 changes to a reentrant angle, and assumes the same just at a time when the door reaches its extreme open position, so that the left-hand angular strip 15 falls into the angle and checks the further opening movement of the door. The latter during its travel has been sustained by two moving pivots 21 and 22, these points having moved to the right along a horizontal line as shown in the diagram. This flows from the fact that the lower portion of the levers 23 and 24 is of about the same length as the bars 26 and 27, and while the intermediate pivots are moving over the arcs shown, the moving pivots 21 and 22 are swinging beneath their respective moving fulcrums 23', 24' as will be clear, such action being permitted by the link construction at the top. The inner pivots 6', 7' of the links are normally spaced about the same distance as the stationary pivots 6 and 7 on the bracket 5, and both pairs stand coincident with the inner edge 40 of the door opening.

It follows from this disposition of the lever mechanism that in either open or closed position one reentrant angle rests against an angle strip 15, and therefore stops to prevent further movements of the door are not necessary when this improved form of hanger is employed, although I may use them if desired and have shown them in the drawings. As all lever mechanism is arranged between the sections 9 and 10 of the door excepting the lower ends of the bars, it is thoroughly protected from the weather on the exterior and from freight on the interior.

Secured to the outer side wall of the car adjacent to the edge of the door opening remote from the levers is a vertical abutment or weather strip 28, having the edge thereof adjacent to the door opening formed 60 with an offset lip 29, while secured to the adjacent edge of the door is a weather strip 30, formed with lips 31 adapted to engage under the lip 29. Secured to the side wall of the car adjacent to the other edge of 55 the door opening is a metal strip 32 having

the edge thereof remote from the door opening formed with an outwardly offset lip 33, while fastened to the adjacent edge of the door is a strip 34 having the outer edge thereof formed with inturned lips 35 adapted to engage beneath the lip 33. These various strips and lips coat with one another to hold the door against outward movement under the weight of the material in the car and form tight connections between the side edges of the door and the wall of the car as a weather protection. 70 75

36 indicates a shield or protector that is bolted or otherwise secured to the side of the car adjacent to the roof and overhangs the path of movement of the upper edge of the door and its associated parts from the elements. 80

It will be seen that I have provided a car door which is strong and durable in construction and which will withstand rough usage, while the lever mechanism insures easy operation of the door at all times, as the sagging of the car or the bulging of the sides, in no way, bind the door. Furthermore, it will be noted that this lever mechanism may be employed in connection with any style of door. 90 95

I claim:

1. In a door hanger, the combination with 95 a door comprising outer and inner spaced sections, and strips between the opposite edges of said sections, each strip having within its length an angle facing toward the other strip; of a wall structure having a door 100 opening, a pair of fixed pivots beneath the edge of said opening, a pair of links pivoted at their outer ends to said structure and with their inner ends respectively above said stationary pivots, a pair of levers pivotally connected at their upper ends with the inner ends of the links and at their lower ends with the door near the lower edge of the latter, and a pair of bars pivotally mounted at their lower ends on said stationary pivots 105 and pivotally connected at their upper ends to points intermediate the ends of said levers, whereby in either extreme position of the door one bar and the upper portion of its corresponding lever will form a reentrant 110 angle corresponding and contacting with the angular face of one of said strips, all the hanger mechanism excepting the lower pivots and the supporting pivots for the links being inclosed within the door structure. 115 120

2. In a door hanger, the combination with a door structure including upright strips at its side edges, each strip having within its length an angle facing toward the other strip; of a wall structure having a door 125 opening, a pair of fixed pivots beneath and a pair of links pivoted above the edge of said opening, a pair of levers pivoted at their upper ends to said links and at their lower ends to the door, and a pair of bars pivoted 130

at their lower ends to said fixed pivots and at
their upper ends to intermediate points on
said levers respectively, whereby in either
extreme position of the door one bar and the
5 upper portion of one lever form a reentrant
angle corresponding and contacting with the
angular face of one of said strips.

In testimony whereof I affix my signature
in presence of two witnesses.

OSCAR ILLI.
